P. W. NELSON

SURGICAL APPLIANCE

Filed Oct. 19, 1925

Inventor:
Peter W. Nelson:

By Chas. T. Johnson
Atty.

UNITED STATES PATENT OFFICE.

PETER W. NELSON, OF CHICAGO, ILLINOIS.

SURGICAL APPLIANCE.

Application filed October 19, 1925. Serial No. 63,301.

This invention relates to improvements in appliances for assisting anatomical organs in the performances of their natural functions, as well as to the general class of surgical appliances, wherein a two-fold use of such a device may be employed, to-wit: by surgeons, or doctors, in holding a member of the human body in desired position and condition for cauterization or medical treatment, as well as to give assistance in the performance of its natural functions.

The object of the invention is, the provision of a device, of the above general character, which shall be simple and inexpensive in construction, strong, durable and highly efficient in operation, with its parts so made and arranged that it can be readily, quickly and securely applied to the member and in such a manner as to be easily and quickly removed.

Another object is, to provide means for clamping and supporting, near its junction with the human body and scrotum, the generative organ of a man as well as the upper part of the scrotum, in such a way that the inflowing blood, through the deep laying arteries, will be dammed and the back flow retarded or checked, through the veins lying close to the upper surface of the member, thus causing the blood to be confined, in the member, and producing the desired result or rigidity.

Further objects and advantages of the invention will be disclosed in the following description and explanation, which will be more readily understood when read in conjunction with the accompanying drawing, in which an embodiment of the invention is illustrated; it being understood that modifications and changes can be resorted to without departing from the spirit of the invention, so long as they fall within the scope of the claims, forming a part hereof.

In the drawing:—

Figure 1, is a side view in elevation of an appliance embodying the invention, showing it in about its operative position.

Figure 2, is a front perspective view of the appliance detached, and

Figure 3, is a rear view in elevation, showing the means for attaching and detaching it.

Like numerals of reference designate corresponding parts throughout the different views of the drawing.

Referring now more particularly to Figs.

1 and 2, of the drawing, it will be seen and understood that the device comprises an apron, or member, 5, made of sheet rubber or any other pliable and elastic material. 60 This apron or member is widened laterally, as shown, and has, at about its longitudinal middle, on its front surface, an elastic, tubular, sleeve 6, preferably integral therewith, of any suitable dimensions, to receive 65 and clamp or resiliently hold that portion of the generative organ 7, adjacent to the upper portion and juncture therewith of the scrotum 8, and body 9, of the male body. This sleeve, like the apron or member 5, is 70 soft, more or less flexible and elastic, and may project any distance forwardly from the apron or member 5, but somewhat less than one inch, has been found to be quite sufficient for obtaining the proper function 75 of said sleeve on the organ 7.

It will be observed that each of the laterally extended portions 10, and 11, of the member 5, is reduced outwardly, to form 80 band-like straps or flaps, and that the free end of the portion 10, is provided with an enlargement or knob 12, while the free end of the portion 11, is likewise furnished with an enlargement or knob 13, to aid in applying the device and in removably fastening it in 85 position.

The upper central portion of the apron or member 5, may be fashioned with some degree of fullness, as at 14, to adapt said portion to more readily conform to the lower front portion of the abdomen and to more effectively assist in securing the device in position, for it will be understood, by reference to Figs. 1, and 3, of the drawing, that the strap or portion 11, is passed twice 90 around the neck or juncture of the scrotum 95 before being tied at the back thereof, as shown in Fig. 3, of the drawing.

This manner of fastening the device is the preferred way, but other ways or means, for 100 said purpose, may be employed, without a departure from the spirit of the invention.

To use the appliance the generative organ 7, may be annointed with a suitable lubricant, such as vaseline, or better, with witch hazel jelly, and the sleeve 6, of the device, can be easily slipped on the organ 7, from the free end of the same, so as to encompass and clamp or press around the same, at about its juncture with the scrotum and body, as 105 shown in Fig. 1, of the drawing, when it is 110 obvious that the portion 10, may be stretched

rearwardly on one side of the scrotum, by pulling on the enlargement 12, in the proper direction. The elasticity of the apron or member 5, and its portion 10, will permit the 5 said enlargement 12, to assume about the position shown in Fig. 3, when it is apparent that the portion or strap 11, can be extended from the other side and rearwardly of the neck of the scrotum, then under the enlargement 12, and forwardly and entirely around that portion of the apron above the sleeve 6, then upwardly around the extremity of the portion 10, just in front of its enlargement 12, and then looped or tucked under itself to 10 be easily released, by pulling on its knob 13, thus releasing the portion 11, and allowing it to be unwrapped and the device quickly removed.

It will be understood that the elasticity of 20 the device is such as to permit, in putting the device on, a free flow of blood towards the free end of the organ 7, through the deeply lying arteries, yet to so check or retard the return flow through the superficial veins as 25 to confine the blood in the organ and thus

produce the desired result. The act of slipping the sleeve 6, on the organ, will in itself cause the flow of blood to the organ.

Having thus fully described the invention, what is claimed and desired to be secured by 30 Letters Patent is—

An appliance of the class described consisting of an elastic apron or member elongated laterally and having between its lateral ends an elastic sleeve extended forwardly from said apron, one of said elastic lateral portions being longer and much narrower than the other elastic lateral portion and each provided at its end with an enlargement, whereby the shorter portion may be 40 disposed at one side of and to the rear of the neck of the scrotum, and whereby the longer portion may be disposed at the other side of and rearwardly of the scrotum, then extended forwardly and entirely around that portion of the apron above the sleeve, then upwardly around the extremity of the shorter portion in front of its enlargement, and then tucked under itself. 45

PETER W. NELSON.
